HUM ELIMINATOR

William Ray Kiefer, Rockford, Ill., assignor to
Sundstrand Engineering Co., Rockford, Ill., a
corporation of Illinois

Application December 23, 1939, Serial No. 310,686

4 Claims. (Cl. 103—224)

The invention relates generally to the elimination of hum in hydraulic circuits, particularly oil burner circuits, and has as a general object to provide a new and improved construction accomplishing that result.

A more particular object of the invention is to provide a hum eliminator, adapted for connection in circuit with a pump, having a non-metallic diaphragm disposed to have the intake fluid of the pump flow over one face thereof and the by-pass fluid flow over the other face thereof.

Yet another object is to provide a hum eliminator device having a non-metallic diaphragm secured between two casing sections each section having an inlet and a discharge port and a baffle directing the fluid flowing through the section into contact with and over the face of the diaphragm.

Other objects and advantages will become apparent from the following detailed description, taken in connection with the accompanying drawing, in which:

Fig. 1 is a hydraulic circuit incorporating a hum eliminator device embodying the features of the invention. The hum eliminator device is shown partially in section.

Fig. 2 is a sectional view taken approximately along the line 2—2 of Fig. 1.

Fig. 3 is a fragmentary view showing the hum eliminator device of Fig. 1 conditioned for connection in a single line fluid system.

While the invention is susceptible of various modifications and alternative constructions, it is shown in the drawing and will be described hereinafter in a preferred embodiment. It is not intended, however, that the invention is to be limited thereby to the specific construction shown, but it is intended to cover all modifications and alternative constructions falling within the spirit and scope of the invention as defined in the appended claims.

While the principle of this invention may be embodied in various devices, including directly in a pump, it is for purposes of disclosure herein shown as embodied in a separate unit, generally designated 5, and connected in circuit with a fuel pump 6 which may take any conventional construction. The pump has an inlet port 7 to which fluid is supplied through a suction line 8, a discharge port 9 adapted for connection to an oil burner nozzle or the like, and a by-pass return port 10 which communicates with a return line 11 for returning to the tank or reservoir the excess of fluid pumped over that flowing through the discharge port 9.

As shown herein, the hum eliminator comprises a hollow casing formed of separable and symmetrical sections 12 and 13. Each section has a bowl shaped portion 14, a semi-cylindrical portion 15 opening to the bowl shaped portion through the bottom thereof, and an annular radially outwardly projecting flange 16. The sections 12 and 13 are secured together by any suitable means, such as bolts 17, and clamped between the flanges 16 of the sections is a non-metallic diaphragm 18 which divides the hum eliminator into two chambers. To adapt the unit 5 for connection in a hydraulic circuit, each section is provided with a pair of ports 19 formed in the ends of the semi-cylindrical portion so as to be disposed opposite one another. One port 19 of the section 12 (the upper one as viewed in Fig. 1) is connected to the suction line 8, while the other port 19 of the section 12 is connected to a continuation 8' of the suction line. Similarly, the upper port 19 of section 13 is connected to the return line 11, while the lower port is connected to a continuation 11' of the return line.

It is a feature of this invention that the fluid flowing through the hum eliminator device is made to flow over and in contact with the diaphragm 18 in order that the hum may be effectively eliminated from the circuit. Accordingly, each section has an imperforate baffle 20 which is anchored in the cylindrical portion 15 intermediate the ends of the cylindrical portion and disposed in a plane at right angles to a line connecting the ports 19. This baffle 20, as best seen in Fig. 2, extends the full diameter of the semi-cylindrical portion 15, as well as the full diameter of the bowl shaped portion 14, and projects inwardly from the semi-cylindrical portion toward the diaphragm 18 a substantial distance. As a result, fluid drawn in through the extension 8' of the suction line may not pass directly to the suction line 8, but must flow laterally around the inner edge of the baffle 20 and thus must flow over and in contact with the face of the diaphragm 18. Such flow of the fluid over the face of the diaphragm has resulted in a much more effective elimination of hum from the circuit than has ever been accomplished before. This is particularly true when the hum eliminator device 5 is so connected, either by connection in the circuit externally of the pump or by incorporation as a unitary part of the pump, that the suction or intake fluid is in one of the chambers formed by the diaphragm while

the by-pass return fluid is in the other chamber formed by the diaphragm 18.

While the invention herein disclosed is preferably utilized in a circuit having a suction and a by-pass return line, it may readily be adapted for use in a single line system, that is, one having no return line. To adapt the invention for such use, the ports 19 of one of the sections are simply plugged to form an air chamber, while the ports 19 of the other section are connected in the suction or intake line to the pump the same as above described. Fig. 3 shows the unit 5 adapted for such use with a single line circuit and shows the section 13 having its ports 19 closed by plugs 21 screw threaded into the ports.

It is believed apparent from the foregoing that I have perfected a vastly improved means or device for eliminating hum in hydraulic circuits, particularly oil burner circuits in which such hum is commonly prevalent and most obnoxious. My hum eliminator means has been found to be particularly effective and this is believed in large part due to the construction wherein the fluid in the circuit actually flows through the hum eliminator device and, more particularly, flows over and in contact with the diaphragm incorporated in the device. In addition to being unusually effective in the elimination of hum, my invention has the additional advantages that it may readily be incorporated in existing circuits without difficulty, and is adaptable for use both with a circuit having a by-pass return line or with circuits not having such by-pass return line.

I claim as my invention:

1. A fluid circuit comprising, in combination, a pump having an inlet port, a discharge port and a by-pass port, an intake line connected to the intake port of said pump, a by-pass return line connected to the by-pass port of said pump, and a hum eliminator device comprising a hollow casing, a non-metallic diaphragm dividing said casing into two chambers, one of the

chambers being connected in the intake line and the other of said chambers being connected in the by-pass line to have the fluid flowing in the lines flow through the chambers.

- 5 2. In a fluid circuit, a pump having an intake port, a discharge port and a by-pass return port, and means for eliminating hum including a non-metallic diaphragm, said means being connected in the intake side of said pump to have the intake fluid flow over one face of said diaphragm, and connected in the by-pass return side of the pump to have the by-pass fluid flow over the opposite face of the diaphragm.
- 10 3. A hum eliminator device for use in a fluid circuit having a pump with an intake port, a discharge port, and a by-pass return port including a non-metallic diaphragm forming a yieldable common wall for a pair of chambers, the device being connected in the circuit to have the intake fluid flow over one face of said diaphragm, and the by-pass return fluid flow over the other face of said diaphragm.
- 15 4. A hum eliminator device for use in a fluid circuit having a pump with an intake port, a discharge port and a by-pass return port, a suction line connected to the intake port, and a by-pass return line connected to the return port comprising a casing composed of separable sections, a non-metallic diaphragm secured between said sections to divide the casing into two separate chambers, a pair of ports opening to one of said chambers for connection of said chamber in the suction line of the circuit, a pair of ports opening to the other of said chambers for connection of said other chamber in the return line of the circuit, and a baffle in each of the sections of said casing disposed between said ports and extending towards said diaphragm but short thereof to cause the fluid flowing through the chamber to pass over and in contact with the fact of said diaphragm.
